VALVE AND STRAINER UNIT

Mardig Hovanian, New York, N. Y.

Application March 25, 1947, Serial No. 737,080

10 Claims. (Cl. 4—287)

1

This invention relates to drain devices for insertion in outlets of basins, sinks and the like, and more particularly to a combination valve and strainer adapted to be removably associated with a drain outlet.

It is primarily within the contemplation of this invention to provide a valve and strainer construction which will be conveniently adaptable for use in the basins of beauty parlors and barber shops where it is necessary not only to readily control the flow of water into the outlet, but also quickly and easily to remove the entire unit for cleaning and repair purposes.

It is also an important object of my invention to enable the unit to be readily and firmly attached to the outlet fixture, whereby it will remain in place and securely held against the dislodgment.

It is a further object of my invention to enable the unit to be readily disconnected from the outlet fixture by a simple manipulation. And in this aspect of my invention it is another object to effect such disconnection without the employment of any special outwardly disposed disconnecting members which might interfere with the operator or cause injury to the operator or customer. In a preferred construction of my invention, this object is accomplished by providing the valve member with means for detachably holding the unit in place.

Another object of this invention is to provide means for enabling the unit to be readily assembled, as well as disassembled for cleaning purposes or repair.

And it is within the further contemplation of my invention to enable the above-mentioned objectives to be attained by a simple, readily fabricated and inexpensive device.

Other objects, features and advantages will appear from the drawings and the description hereinafter given.

Referring to the drawings,

Figure 1 is a side elevation of a preferred embodiment of my invention shown operatively connected to an outlet fixture which is shown in section, a fragment of the device being broken away for clarity, the invention being illustrated in open or draining condition;

Figure 2 is a section of Figure 1 taken along line 2—2, the locking member being shown in full lines in its normal locking position, and in dot-dash lines in a retracted and lowered position;

Figure 3 is a section of Figure 2 taken along line 3—3;

2

Figure 4 is an enlarged fragmentary sectional plan of Figure 1 taken substantially along line 4—4;

Figure 5 is a view similar to Figure 4, but showing a different relative positioning of the two coacting shells whereby the outlet apertures are blocked and the device is in its closed condition;

Figure 6 is a fragmentary section of Figure 4 taken substantially along the line 6—6 thereof;

Figure 7 is a perspective view of the resilient locking member employed in my invention, a portion of the upper bridge portion being broken away for clarity.

Figure 8 is an enlarged fragmentary elevation of a portion of the device of Figure 1, showing the pressed-out T formation on the outer shell to provide limiting movements therefor, as well as a bayonet joint for disassembling the two shells; and

Figure 9 is a sectional plan of Figure 8 taken substantially along line 9—9 thereof.

In the preferred form of my invention illustrated in the drawings, the construction includes two coacting shells 10 and 11, the former containing an inner preferably cylindrical wall 12 bridged at the top by an upper wall 13, and the latter containing an outer preferably cylindrical wall 14 slidably and rotatively mounted over the said wall 12. The said inner shell 10 contains a lower outwardly extending flanged base 15 upon which the lower edge 16 of shell 11 rests when it is in its lowermost operative position, as will more clearly hereinafter appear.

Outer shell 11 contains an upper portion 17 consisting, in its preferred form, of a lateral cylindrical portion 18 of reduced diameter and a top closure wall 19. In the specific form illustrated, the upper wall 19 contains a central raised portion 20 to accommodate a screw-head, as will hereinafter appear. Furthermore, the lateral wall 18 of upper portion 17 is knurled or otherwise serrated at circumferential region 21, so as to provide a conveniently rough gripping surface for manual rotary manipulation. The proportion of shells 10 and 11 is such that when the outer shell 11 is in its lowermost position as illustrated in Figure 2, the upper closure wall 19 of said shell is in predetermined spaced relation to the upper wall 13 of the inner shell 10, providing a space or compartment 22 therebetween to accommodate certain yieldable securing means for a locking member, which will now be described.

The said upper wall 13 contains a central aperture 23, the preferred construction illustrated

comprising a cylindrical wall 24 pressed upwardly from wall 13 and surrounding said aperture 23. The said wall 13 also contains two diametrically opposed openings 25 through which extend the two depending legs 26 of the resilient locking member 27, clearly illustrated in perspective in Figure 7. This inverted U-shaped member contains a horizontal top or cross-piece 28, the center of which is punched inwardly to provide an aperture 29 surrounded by cylindrical wall 30. The legs 26 each have at their lower extremities the outwardly disposed locking flanges 31, the said legs 26 being normally disposed in a predetermined outwardly projected position, as will more clearly hereinafter appear.

In the assembled position of said resilient locking member 27 particularly as illustrated in Figure 2, the cross-piece 28 thereof is disposed in proximity to upper wall 19 of the outer shell 11, and in parallel spaced relation to the upper wall 13 of the inner shell 10. A stud 32 extends vertically downwardly from the hole 29 through the lower hole 23, the head 33 and washer thereunder resting upon the cross-piece 28, and the shank of the stud extending to a predetermined point below wall 13, the nut 34, mounted over said shank, being in engagement with the underside of wall 13. Mounted over the shank, and preferably over the said cylindrical walls 24 and 30 is the helical spring 35. This spring normally is under compression when in operative use, so that it tends to separate walls 13 and 28, thereby providing for a firm securement of the parts, and for a tight waterproof seal upon the basin seat, as will hereinafter be described.

In the form of my invention illustrated, the cylindrical walls 12 and 14 of the two coacting shells are each provided with correspondingly disposed and proportioned outlet apertures 36 and 37. These apertures are arranged alternately in spaced vertical rows of three and two, so that in the open position illustrated in Figures 1, 2, 3 and 4, all holes coincide, so as to permit water to pass therethrough. When the outer shell 11 is rotatably manipulated to its closed position, the rows of apertures will be moved out of coincidence, so that each of the outlet apertures 37 of the outer shell will be covered by a solid portion of the inner wall 12.

The lower portion of the outer wall is pressed out to form a T formation 38 consisting of a horizontal portion 39 and a vertical portion 40. The lower portion of the inner wall 12 is also pressed out to provide a bump or protrusion 41 which extends into the recessed portion of the T 38, and is adapted to slidably move along the inner wall thereof. In the position shown in Figure 9, bump 41 is disposed against the extreme right side of horizontal portion 39; and by rotatably manipulating the outer shell 11 in a clockwise direction, the said bump will be brought in engagement with the extreme left end of the said horizontal portion 39. In this manner, two extreme operative positions—the open and the closed position—are set, so that an operator can readily selectively turn outer shell 11 from one to the other of these positions. In the open position, as illustrated in Figure 4, the outlet apertures 36 and 37 coincide, and in the closed position, the outer apertures 37 are obstructed, as shown in Figure 5. The vertical portion 40 of the T is provided so as to enable the shell 11 to be removed. When this is required, the outer shell 11 is rotated until the bump 41 is directly above vertical portion 40, whereupon the shell 11 can be

vertically moved upwardly, said portion 40 constituting a passageway for bump 41, substantially like a bayonet construction.

The flange 15 of inner shell 10 contains, along the upper periphery thereof, a marking 42 indicating the open position, and another marking 43 indicating the closed position. The outer shell 11 has pressed out from the lower periphery thereof an indicator or pointer 44, so positioned that when this indicator is disposed at line 42, the outlet apertures would be in coincidence, as shown in Figure 4, and when disposed at the closed line 43, the apertures will be out of coincidence and the device in its closed condition.

The valve and strainer unit above described is adapted for attachment to a conventional drain outlet in a basin or sink, such as is shown in Figures 1 and 2. The basin 45 has a central outlet opening 46 into which extends the basin fitting 47 containing an outlet shell 48 with an upper peripheral flange 49 resting upon the floor 50 of the basin. The shell 48 contains, in the form illustrated, two oppositely disposed openings 51, these generally being intended to accommodate therein holding extensions of a strainer disc. This disc is removed for best operative results with my invention.

Before attaching the device to a basin, it is preferred that the outer shell be removed, in the manner above described. Thereafter the legs 26 are pressed inwardly and the entire member 27 pressed downwardly against the action of spring 35, and the device placed within the outlet, substantially as shown in Figure 2, the dot-dash lines indicating the retracted and lowered position of the locking member 27. When the flanges 31 are disposed adjacent the openings 51 of the outlet shell, the inward pressure upon the legs and then the downward pressure upon the member 27 is released, whereupon the legs 26 will spring outwardly into said openings, and the entire member 27 will be lifted upwardly by the action of spring 35, until the lips 31 engage the upper walls 52 of the openings 51. When this occurs, the entire device is firmly held anchored in place. Since there can be no further upward movement of the member 27, the spring 35 now presses the entire inner member 10 downwardly upon the flange 49 of the outlet fitting to provide a firm fit. To effect a tight waterproof seal, a gasket 53 is interposed between flanges 45 and 49.

To place the device in condition for operation, the outer shell 11 is slid over the inner shell 10 to the lowermost position, and then rotatively manipulated, in the manner aforesaid, to open or close the outlet apertures.

The device above described thus provides a convenient valve and strainer arrangement for basins, one that is presentable in appearance, that offers a minimum of obstruction to the user of the basin, that is easily manipulable, that is readily assembled and disassembled for cleaning or replacement purposes, and that is relatively simple in construction.

In the above description, the invention has been disclosed merely by way of example and in preferred manner; but obviously many variations and modifications may be made therein which will still be comprised within its spirit. It is to be understood, therefore, that the invention is not limited to any specific form or manner of practicing same, except in so far as such limitations are specified in the appended claims.

I claim:

1. In a valve and strainer unit adapted for association with a basin outlet of the type having an outlet fitting extending into the outlet and having two openings in the lateral wall thereof, the combination consisting of two coacting shells one stationary and the other rotatable, the latter being in rotatable engagement with the former, the shells being disposed over and in vertical alignment with said fitting, said shells each containing outlet apertures arranged for registry when the rotatable shell is in a predetermined open position and obstructed when it is in a predetermined closed position, the inner of said shells containing an apertured upper wall, a resilient locking member comprising a cross-piece and at least two legs depending therefrom and extending downwardly through said upper wall and into said outlet fitting and yieldably urged outwardly, said legs having outwardly disposed lips extending into the said openings of the outlet fitting, and spring means between said upper wall and said cross-piece and under compression, said locking member being urged upwardly by the spring means whereby said lips are brought and maintained in yieldable locking engagement with the upper walls of said openings, and the inner of said shells being urged downwardly by the spring against the underlying floor of the basin.

2. In a valve and strainer unit adapted for association with a basin outlet of the type having an outlet fitting extending into the outlet and having two openings in the lateral wall thereof, the combination consisting of two coacting shells one stationary and the other rotatable, the latter being in rotatable engagement with the former, the shells being disposed over and in vertical alignment with said fitting, the stationary shell containing a bottom flange supported by the floor of the basin, the bottom edge of the rotatable shell resting upon said flange, said shells each containing outlet apertures arranged for registry when the rotatable shell is in a predetermined open position and obstructed when it is in a predetermined closed position, the inner of said shells containing an apertured upper wall, a resilient locking member comprising a cross-piece and at least two legs depending therefrom and extending downwardly through said upper wall and into said outlet fitting and yieldably urged outwardly, said legs having outwardly disposed lips extending into the said openings of the outlet fitting, and spring means between said upper wall and said cross-piece and under compression, said locking member being urged upwardly by the spring means whereby said lips are brought and maintained in yieldable locking engagement with the upper walls of said openings, and the inner of said shells being urged downwardly by the spring against the underlying floor of the basin.

3. In a valve and strainer unit adapted for association with a basin outlet of the type having an outlet fitting with an upper peripheral flange resting upon the floor of the basin and a cylindrical wall extending into the outlet and having two openings in said wall, the combination consisting of two coacting shells one stationary and the other rotatable, the latter being in rotatable engagement with the former, the shells being disposed over and in vertical alignment with said fitting, the stationary shell containing a bottom flange supported by the said upper flange, the bottom edge of the rotatable shell resting upon said bottom flange, said shells each containing

outlet apertures arranged for registry when the rotatable shell is in a predetermined open position and obstructed when it is in a predetermined closed position, the inner of said shells containing an apertured upper wall, a resilient locking member comprising a cross-piece and at least two legs depending therefrom and extending downwardly through said upper wall and into said outlet fitting and yieldably urged outwardly, said legs having outwardly disposed lips extending into the said openings of the outlet fitting, and spring means between said upper wall and said cross-piece and under compression, said locking member being urged upwardly by the spring means whereby said lips are brought and maintained in yieldable locking engagement with the upper walls of said openings, and the inner of said shells being urged downwardly by the spring against the upper peripheral flange of the outlet fitting.

4. In a valve and strainer unit adapted for association with a basin outlet of the type having an outlet fitting with an upper peripheral flange resting upon the floor of the basin and a cylindrical wall extending into the outlet and having two openings in said wall, the combination consisting of a cylindrical inner shell, a cylindrical outer shell rotatively mounted thereover, the inner shell having a bottom flange overlying and supported by said upper flange of the fitting, a gasket between said flanges, the shells being in substantial axial alignment with the said outlet fitting, the bottom edge of the outer shell resting upon said bottom flange, said shells each containing outlet apertures arranged for registry when the outer shell is in a predetermined open position and obstructed when it is in a predetermined closed position, the inner shell containing an apertured upper wall, a resilient locking member comprising a cross-piece and at least two legs depending therefrom and extending downwardly through said upper wall and into said outlet fitting and yieldably urged outwardly, said legs having outwardly disposed lips extending into the said openings of the outlet fitting, and spring means between said upper wall and said cross-piece and under compression, said locking member being urged upwardly by the spring means whereby said lips are brought and maintained in yieldable locking engagement with the upper walls of said openings, and the inner shell being urged downwardly by the spring against the upper peripheral flange of the outlet fitting.

5. In a valve and strainer unit adapted for association with a basin outlet of the type having an outlet fitting extending into the outlet and having two openings in the lateral wall thereof, the combination consisting of a cylindrical inner shell, a cylindrical outer shell rotatively mounted thereover, the shells being disposed over and in vertical alignment with said fitting, said shells each containing outlet apertures arranged for registry when the outer shell is in a predetermined open position and obstructed when it is in a predetermined closed position, said shells containing upper walls in spaced relation thereby forming an upper shell compartment, the lower of said two walls having apertured portions therein, a resilient locking member comprising a cross-piece disposed within said compartment and two legs depending therefrom and extending downwardly through said apertured portions and into said outlet fitting and yieldably urged outwardly, said legs having outwardly disposed lips extending into the said openings of the outlet fitting, and

spring means disposed within said compartment between the cross-piece and the lower of said two walls and under compression, said locking member being urged upwardly by the spring means whereby said lips are brought and maintained in yieldable locking engagement with the upper walls of said openings, and the inner shell being urged downwardly by the spring against the underlying floor of the basin.

6. In a valve and strainer unit adapted for association with a basin outlet of the type having an outlet fitting extending into the outlet and having two openings in the lateral wall thereof, the combination consisting of a cylindrical inner shell, a cylindrical outer shell rotatively mounted thereover, the shells being disposed over and in vertical alignment with said fitting, said shells each containing outlet apertures arranged for registry when the outer shell is in a predetermined open position and obstructed when it is in a predetermined closed position, said shells containing upper walls in spaced relation thereby forming an upper shell compartment, the lower of said two walls having two oppositely disposed apertures and a central hole therein, a resilient locking member comprising a cross-piece disposed within said compartment and two legs depending therefrom and extending downwardly through said apertures and into said outlet fitting and yieldably urged outwardly, said legs having outwardly disposed lips extending into the said openings of the outlet fitting, said cross-piece having a central hole in vertical registry with the lower central hole, a stud extending downwardly through both of said holes, a nut in threaded engagement with the lower portion of the stud and bearing against the underside of the lower of said walls, a helical spring mounted over the shank of said stud within said compartment and in pressing engagement with the lower of said walls and the said cross-piece, said locking member being urged upwardly by the spring whereby said lips are brought and maintained in yieldable locking engagement with the upper walls of said openings, and the inner shell being urged downwardly by the spring against the underlying floor of the basin.

7. In a valve and strainer unit, the combination according to claim 6, the said central holes being each surrounded by a cylindrical wall pressed out respectively from the cross-piece and the lower of said walls into said compartment, opposite ends of the spring being disposed around said walls.

8. In a valve and strainer unit adapted for association with a basin outlet of the type having an outlet fitting extending into the outlet and having two openings in the lateral wall thereof, the combination consisting of a cylindrical inner shell, a cylindrical outer shell rotatively mounted thereover, the shells being disposed over and in vertical alignment with said fitting, the inner shell having a bottom flange supported by the floor of the basin, the bottom edge of the outer shell resting upon said flange, said flange containing markings thereon indicating predetermined open and closed positions, the lower portion of the outer shell having forced out therefrom a pointer adapted to coincide with one of said markings when the outer shell has been operatively manipulated to said positions, said shells each containing outlet apertures arranged for registry when the outer shell is in said open position and obstructed when it is in said closed position, the inner shell containing an apertured

upper wall, a resilient locking member comprising a cross-piece and two legs depending therefrom and extending downwardly through said upper wall and into said outlet fitting and yieldably urged outwardly, said legs having outwardly disposed lips extending into the said openings of the outlet fitting, and spring means between said upper wall and said cross-piece and under compression, said locking member being urged upwardly by the spring means whereby said lips are brought and maintained in yieldable locking engagement with the upper walls of said openings, and the inner shell being urged downwardly by the spring against the underlying floor of the basin.

9. In a valve and strainer unit adapted for association with a basin outlet of the type having an outlet fitting extending into the outlet and having two openings in the lateral wall thereof, the combination consisting of a cylindrical inner shell, a cylindrical outer shell rotatively mounted thereover, the shells being disposed over and in vertical alignment with said fitting, said shells each containing outlet apertures arranged for registry when the outer shell is in a predetermined open position and obstructed when it is in a predetermined closed position, the outer shell having a T groove pressed outwardly therefrom and extending upwardly from the lowermost edge of said shell, the inner shell having a protrusion extending into said groove and adapted to limit the rotary movement of the outer shell upon engagement with the extreme terminals of the horizontal portion of the T, said extreme terminals representing said open and closed positions of the outer casing, the inner shell containing an apertured upper wall, a resilient locking member comprising a cross-piece and two legs depending therefrom and extending downwardly through said upper wall and into said outlet fitting and yieldably urged outwardly, said legs having outwardly disposed lips extending into the said openings of the outlet fitting, and spring means between said upper wall and said cross-piece and under compression, said locking member being urged upwardly by the spring means whereby said lips are brought and maintained in yieldable locking engagement with the upper walls of said openings, and the inner shell being urged downwardly by the spring against the underlying floor of the basin.

10. In a valve and strainer unit, the combination according to claim 6, the top of the outer casing being of reduced proportions and surrounding and completely enclosing the said compartment, whereby it could be conveniently grasped for manual manipulation, and the cross-piece of the locking member being in close proximity to the upper wall of the outer casing.
